DEVICE FOR TAKING UP THE WEAR
OF PIECES

Gaston Lucien Debaecker, Paris, France

Application November 16, 1933, Serial No. 698,373
In France November 19, 1932

8 Claims. (Cl. 131—37)

It often occurs that, in a machine, a piece movable with respect to another one must be of a constant length. This is the case, for instance, when said piece must periodically close an electric contact with another piece, or also when said first mentioned piece is provided with a sharp edge so as to perform some cutting operation. The piece that is being considered may be either stationary (in which case it is the other piece, with which it cooperates, that moves) or moving with a translatory or rotary motion. In order to suitably perform its contacting, cutting, or any other, function, the length of the piece that is being considered must be kept constant or at least must not be allowed to fall under a certain limit. Now, due to the fact that it performs said function, the piece in question wears off, either as a result of friction (in the case of a contact); or as a result of sharpening (in the case of a cutting edge). It is therefore necessary, after a certain time, to take up the wear that has taken place and to bring the piece back to its initial length.

The object of the present invention is to provide a device for effecting the operation above described. Such a device is applicable whenever it is desired to take up the wear of a piece the length of which must remain constant or substantially constant. In the following description of a specific example of a device according to the present invention it will be supposed that said device is used in connection with a rotary knife for cutting the tube of paper filled with tobacco in a cigarette making machine in which this tube is fed in a continuous manner. But it should be well understood that the present invention is not in any way limited to this application and that its object is a device for taking up the wear of pieces of the type above referred to, whatever be the machine of which said pieces are a part.

A preferred embodiment of the present invention will be hereinafter described, with reference to the accompanying drawing, given merely by way of example, and in which:

Fig. 1 is a diagrammatical view illustrating the principle of the invention;

Fig. 2 is an elevational view of an embodiment of the device according to the present invention;

Fig. 3 is an end view of the device shown in Fig. 2.

As shown in the diagrammatical view of Fig. 1, the part of the machine the wear of which is to be taken up consists of two elements: a carrier

A and a second element or member B movably interconnected with respect to carrier A. According to the invention, an organ C (rack, endless screw, electric control, etc.) makes it possible to displace element B with respect to element A. This organ C is actuated by another organ D (milled knob, electric contact, etc.).

On the part of the machine that is intended to coact with part A—B (that is to say the stationary part of the machine if part A—B is moving, or the moving part of said machine if part A—B is stationary), there is mounted a member E which, for every stroke of part A—B with respect to the part of the machine with which it coacts may come into contact with piece D. Member E may assume two different positions: the position shown in solid lines for which it comes into contact with organ D and the position shown in dotted lines, for which it cannot act on organ D. Under these conditions, supposing member E to be in its first mentioned, or operative, position, it is clear that it coacts with organ D at every stroke of the moving part of the machine and, through organ C, gradually causes element A to be displaced with respect to element B, thus increasing the total length of part A—B.

On the other hand, a contact member H, operatively connected with the means for moving member E, is positioned across the path of travel of the end of element B that corresponds to the maximum length of part A—B. It will be readily understood that, as soon as element A has been moved with respect to element B a distance sufficient for restoring the combined length of part A—B to its initial maximum value, the end of element B comes to touch contact member H and thus causes member E to be brought into its inoperative position E' in which it no longer cooperates with organ D, so that organ C ceases to produce a relative displacement of element B with respect to element A.

The device above described is brought into operation either manually, when it is judged that the wear of B exceeds the admissible value, or automatically due to the very fact that the length of B has decreased beyond said limit.

In an embodiment of my invention, which will be hereinafter described in a more detailed manner, the means L for operatively connecting member H to member E consist of a spring lever tending to bring back member E into its position E', said lever being maintained against the action of its spring by a pawl the upper part of which comes into engagement with said lever and

the lower part of which constitutes contact member H or is controlled by said contact member.

The specific embodiment of the present invention shown in Figs. 2 and 3 is more particularly adapted to be used in connection with the cutting organs of cigarette making machines.

The cutter 1 (which corresponds to part B of Fig. 1) of cutting arm 3 is held and guided between a supporting part 4 and a spring 5 the strength of which can be varied by means of a screw 6. The end of said cutter 1 that is opposed to its cutting edge is fixed to a block forming a nut 7 engaged on a screw 8 (corresponding to organ C, in Fig. 1). This screw is journalled in arm 3 and its rotation causes nut 7 and consequently cutter 1 to move longitudinally with respect to said arm 3. Screw 8 can be rotated by acting on its milled head 9 (which corresponds to member D of Fig. 1).

20 This first movable part of the device is completed by a second stationary part mounted on the frame of the machine and made as follows:

A lever 11, urged in the upward direction by a spring 12 and limited to two extreme positions 25 by stops 13 and 14 is pivotally mounted on a stationary spindle 10 parallel to the plane in which the cutter is rotating. The right-hand end of said lever 11 is intended to be operated by hand. The portion of said lever that extends 30 obliquely in an upward direction on the left hand side of spindle 10 is adapted to come into engagement with a bent pawl 15 the lower end of which carries a contact roller 16 (corresponding to member H of Fig. 1) intended to limit the 35 relative displacement of cutter 1 and arm 3.

A disk 20 (corresponding to member E of Fig. 1) is adapted to move together with lever 11. This disk 20 is intended to turn milled knob 9, when 40 it is brought into contact with the latter. To this effect, disk 20 may be given a rough periphery, or, better, it may carry on its periphery a tore-shaped rubber ring, which may be replaced, or merely turned about the disk when it is worn at a point. In order to ensure a better adhesion 45 and a sufficiently elastic contact of the edge of disk 20 with milled head 9, I preferably provide an elastic connection between said disk and lever 11 instead of a rigid connection. To this effect, disk 20 is carried by an arm 18 adapted 50 to turn freely about spindle 10 and connected to lever 11 through a spring 19. A stop 17, carried by a projection 21 of lever 11 causes arm 18 to turn in the direction of arrow F when lever 11 is turned in this direction. Under normal conditions of working, levers 11 and 18 are in the 55 positions shown in dotted lines in Fig. 2. If it is assumed, at any time, that the total length of arm 3 and cutter 1 is too short, for ensuring a normal cutting of the cigarettes, it suffices to 60 depress lever 11 so as to bring it from its position shown in dotted lines in Fig. 2 into its position shown in solid lines, without modifying the working conditions of the machine. Lever 11 is locked in this position by the projection 22 of 65 pawl 15. Stop 17 has turned about spindle 10 in a direction opposed to that of arrow F, so that arm 18, urged by spring 19, brings disk 20 into tangential relation to the path of travel of milled knob 9 which, at each revolution of arm, is caused 70 to roll over a portion of the periphery of the rubber ring fitted on disk 20. Therefore, at each revolution of blade carrier 3, screw 8 is caused to rotate through an angle corresponding to a fraction of a turn. Consequently, nut 7 is 75 caused to move intermittently in a direction

parallel to the axis of said screw, thus outwardly displacing cutter 1. After some revolutions, cutter 1 has been sufficiently displaced for coming into contact with roller 16. The latter is then pushed upwardly, thus causing pawl 15, through which lever 11 was locked, to pivot. Projection 22 disengages lever 11, which comes back into its initial position, under the action of its spring. Stop 17 causes arm 18 to rotate together with lever 11. Disk 20 is displaced in the direction of arrow F and screw 8 ceases to be turned at each revolution of arm 3. Cutter 1 then remains in a fixed position with respect to arm 3.

Of course milled knob 9 might be replaced by a star wheel having a number n of radial projections, disk 20 being then replaced by a pin against which the radial projections of the star wheel are caused to strike successively, thus imparting the desired rotary movement to said star wheel.

Also, instead of having the downward movement of lever 11 performed by hand, I may provide any device (for instance controlled by an electric contact) for causing said lever to pivot automatically in a downward direction when the length of cutter 1 has diminished by a given quantity.

In a general manner, while I have described what I deem to be practical and efficient embodiment of my invention, it should be well understood that I do not wish to be limited thereto as there might be changes made in the arrangement, disposition and form of the parts without departing from the principle of my invention as comprehended within the scope of the appended claims.

What I claim is:

1. In a machine comprising two coacting parts movable with respect to each other, the first part including two elements, a carrier and a member movably interconnected with said carrier and adapted to coact with the second part of the machine, a device for taking up the wear of said member, which comprises in combination, means for moving said member with respect to its carrier, means movably carried by said second part of the machine and adapted to be brought into operative position with respect to said first mentioned means for engaging intermittently therewith so as to operatively actuate the same, means for locking the second mentioned means in operative position, and means operatively controlled by said member for bringing said second mentioned means out of operative position as soon as the total length of said member and its carrier has been restored to its initial value.

2. In a machine comprising two coacting parts movable with respect to each other, the first part including two elements, a carrier and a member slidably interconnected with said carrier, and adapted to coact with the second part of the machine, a device for taking up the wear of said member, which comprises in combination a screw journalled in one of said elements, a nut engaging on said screw and rigidly connected to the other element, a rotary member angularly connected to said screw, means, movably carried by said second part of the machine and adapted to be brought into operative position across the relative path of travel of said rotary member, for engaging intermittently therewith so as to operatively actuate it, means for locking said means in operative position, and means operatively controlled by said member for bringing said first mentioned means out of operative position as

soon as the total length of said member and its carrier has been restored to its initial value.

3. A device according to claim 2 in which said rotary member consists of a milled head rigid 5 with said screw.

4. In a machine comprising two coacting parts movable with respect to each other, the first part including two elements, to wit a carrier and a member slidably interconnected with said carrier and adapted to coact with the second part of the machine, a device for taking up the wear

10 of said member, which comprises in combination, a screw journalled in one of said elements, a nut engaging on said screw and rigidly fixed to the

15 other element, a rotary member angularly connected with said screw, means, movably carried by said second part of the machine and adapted to be brought into operative position across the relative path of travel of said rotary member, for

20 engaging intermittently with said rotary member so as to operatively actuate it, a lever operatively connected with said means for controlling the position thereof with respect to said first part of the machine, elastic means for urging said lever

25 toward the position thereof that corresponds to the inoperative position of said means, a movable locking organ adapted to maintain said lever in the position thereof that corresponds to the operative position of said first mentioned means,

and a contact member operatively connected with said locking organ and adapted to cooperate with the first mentioned member for displacing said locking organ so as to release said lever when the total length of said first mentioned member and its carrier has been restored to its initial value.

5. A device according to claim 4 in which said locking organ consists of a pivoted pawl adapted to engage with one end of said lever, and said contact member consists of a roller journalled in 10

said pawl.

6. A device according to claim 2 in which the first mentioned means consist of a disc adapted to frictionally engage said rotary member.

7. A device according to claim 4 in which said first mentioned means consist of a disc carried by said lever and the edge of which is adapted to frictionally engage said rotary member.

8. A device according to claim 4 in which said first mentioned means include a disc, an arm carrying said disc and pivoted to said lever, elastic means urging said arm toward said rotary member, a stop limiting the displacement of said arm with respect to said lever under the action of the last mentioned elastic means, and a frictional 20 element fitted on the periphery of said disc for 25 engaging with said rotary member.

GASTON L. DEBAECKER.
